Primary Examiner — Rachel A. Voorhies*Assistant Examiner* — Benjamin D. Wannemacher(74) *Attorney, Agent, or Firm* — Lippes Mathias LLP(57) **CLAIM**

The ornamental design for a tool holder, as shown and described.

DESCRIPTION

FIG. 1 is a perspective view of a tool holder;
 FIG. 2 is a front plan view thereof;
 FIG. 3 is a rear plan view thereof;
 FIG. 4 is a side view thereof, the opposed side appearing the same;
 FIG. 5 is a top end view thereof; and,
 FIG. 6 is a bottom end view thereof.

The broken lines depict subject matter that forms no part of the claimed tool holder and are provided solely for illustrating the full tool holder.
